THREAD SPOOLING MACHINE

Jan Willem Lubberhuizen, Arnhem, Netherlands,
assignor, by mesne assignments, to American
Enka Corporation, Wilmington, Del., a corpora-
tion of Delaware

Application July 9, 1932, Serial No. 621,535
In Germany July 22, 1931

4 Claims. (Cl. 18—8)

My invention relates to a thread spooling machine in which the spool holders are arranged in pairs, the spool holders of each pair rotating in opposite directions.

5 In machines of this character as now constructed, only one spool of a pair can be wound at one time while the other spool remains stationary, the winding of the second spool necessarily being deferred until completion of the 10 winding of the first spool.

The principal object of my invention is to enable both spools of each or any pair to be wound simultaneously, and to accomplish this object I allocate a spinning nozzle to each spool 15 holder and arranged in cooperative relation with at least each pair of spool holders a shaft or roll extending transversely to and driven independently of the spool holders, the function of the roll being to receive the thread being 20 produced while the spools are being changed.

It will be apparent from what is said above 25 that the purpose of the invention is to better utilize the capabilities of machines of this type, and this factor is of especial significance in view 30 of the demand for yarns of increasingly finer titre, as a consequence of which the output of the machine reckoned in kilograms constantly decreases. This is counteracted by the present invention in accordance with which the several 35 spools are simultaneously wound. The loss resulting from the change of spools is negligible compared with the gain resulting from the simultaneous winding of the several spools, more particularly as the time required for changing the usual present day spinning periods.

The time for changing spools may be further curtailed if the shaft or roll, which is preferably common to all the spool holders and extends transversely thereto, is mounted so as to be capable of being swung into a position over the spools, and if each thread guide is so constructed that the distance between the two threads passing through each thread guide is greatest and the threads are maintained at the extremities of the guide loops at the time that the roll is in its lowermost position to thereby receive the thread during the doffing period and very shortly after the roll is started to be moved to its top position. In this manner the reception of the thread by the spool to be freshly wound is automatically effected, thus greatly simplifying the procedure.

A further reduction of time in changing 55 spools may be brought about by making the

spool holder driving shaft in sections and actuating each section independently. If a long, continuous roll or shaft be used for taking up the thread produced while the spools are being changed, this roll must be made in sections corresponding to the sections of the driving shaft for the spool holders, and in consequence of the sectional construction of the driving shaft the stoppage of the spools may be effected intermittently and, in case the shaft consists of two sections for example, the waste may be reduced by approximately one half.

Existing machines may readily be reconstructed to embody the present invention.

An illustrative embodiment of the invention 70 is shown in the accompanying drawings in which

Fig. 1 shows a cross section of one side of the machine which is two-sided as a rule.

Fig. 2 shows one of the symmetrical halves of the machine side shown in Fig. 1, as seen from 75 the front.

Fig. 3 is a top plan view of the swivelling device the bobbins being omitted for greater clearness.

Fig. 4 shows the arrangement of Fig. 3, as seen 80 from the side.

Fig. 4a shows a detail.

Fig. 5 is a plan view of the thread guide on an enlarged scale.

Fig. 6 is an elevational view of the same.

The bobbin-carriers 1 with their bobbins 2 are arranged in pairs, the left-hand bobbin-carrier rotating counter-clockwise and the right-hand bobbin-carrier rotating clockwise. The bobbin-carriers are driven by a driving shaft 7 through 90 the intermediary of toothed wheels. To each bobbin-carrier 1 appertains a spinning nozzle 3.

Between each pair of bobbins and common thereto is arranged a thread-guide 4 comprising the shank 4a and the two guiding eyes 4b at an angle to the shank, the eyes 4b preferably being bent downwardly out of the plane of the shank 4a. The thread-guide is constructed so that the two threads guided thereby do not touch each other but remain spaced as far apart as possible. 95 To this end, the thread guide construction is such that the two threads are moved outwardly by the resultant of the thread tensions.

The shape of the thread-guide must be such that, while the roller 5 is being swung out, the 100 distance between the two threads carried by it is greater than the clearance of the bobbins to which the said thread-guide appertains.

Extending transversely to the bobbin holder 110 is mounted the long shaft-like roller 5 which

is intended for receiving the spun yarn produced while the bobbins are changed.

The roller 5 is mounted in rocking arms 6 rigidly fastened to the shaft 8 which can be rotated by means of the lever 9 provided with a handle. The lever 9 is provided with a suitable securing device, e.g. a pin 17 engaging with notches 18, 18a of an abutment 19.

The roller 5 is driven as follows: The shaft 8 carries a pair of loose wheels 10, 11 coupled with each other and prevented by a set collar 15 from displacement in an axial direction. Wheel 10 is an ordinary spur gear while wheel 11 is a sprocket wheel. With gear 10 meshes the gear 14 fastened to the shaft 12 whereas the sprocket wheel 11 is connected by a chain 16 to the sprocket wheel 13 fastened to the roller 5.

In turn, shaft 12 is driven by an auxiliary motor 23 through the intermediary of gear train 20, 21, 22. Accordingly, the drive of shaft 12 is independent of the drive of the bobbin-carrier, viz. of shaft 7.

When the arms 6 are being swung out, the gear 10 of the pair of wheels 10, 11 loosely moves about the shaft 8 and thus rolls on the gear 14 of shaft 12.

The operation may be briefly outlined as follows: When the completely wound spools have been removed from the holders 1 and fresh spools placed thereon, the roll 5 is moved from the full line position (Figs. 1 and 2) to the dotted line position 5a. As a consequence of this movement, and because the distance between the two threads guided through each thread guide at the moment the roll is started to move upwardly is greater than the distance apart of the spools to which the thread guide is allocated, the threads are automatically pressed against the rotating spools which are to be freshly wound, so that a new spinning period may commence. It will be understood that the spreading action of the thread guides only lasts during the bottom part movement of the roll 5. As soon as the angle between the part of the thread leaving the spinning bath and running to the thread guide and the part of the thread leaving the thread guide and running to the roller is widened to about 180° the thread guide loses its spreading action but at that moment the threads have already touched the running spools on the spool holders and are taken over thereby.

I claim:

1. In a spooling machine comprising spool holders arranged in pairs and means for simultaneously rotating the holders of each pair in opposite directions, the combination therewith of

a spinning nozzle for each spool holder, thread take-up means common to all the spool holders and extending longitudinally of the machine substantially at right angles to the axes of the spool holders, means independent of the spool holder rotating means for actuating said take-up means, thread guides for the spool holders, and means for angularly moving said take-up means into a position over the spool holders.

2. In a spooling machine comprising spool holders arranged in pairs and means for simultaneously rotating the holders of each pair in opposite directions, the combination therewith of a spinning nozzle for each spool holder, thread take-up means for taking up thread produced during changing of spools, means for actuating said take-up means, thread guides for the spool holders, a thread guide comprising a shank and laterally extending means operable when said take-up means is moved angularly to spread apart the threads guided thereby a distance greater than the distance between the spool holders of a pair of spool holders and means for angularly moving said take-up means into a position over the spool holders.

3. In a spooling machine comprising spool holders arranged in pairs and means for simultaneously rotating the holders of each pair in opposite directions, the combination therewith of a spinning nozzle for each spool holder, thread take-up means for taking up thread produced during changing of spools, means for actuating said take-up means, thread guides for the spool holders, a thread guide comprising a shank and laterally extending guide loops inclined at an angle to the plane of the shank, and means for angularly moving said take-up means into a position over the spool holders.

4. In a spooling machine comprising spool holders arranged in pairs and means for simultaneously rotating the holders of each pair in opposite directions, the combination therewith of a spinning nozzle for each spool holder, a thread guide for each pair of spool holders said thread guide comprising a shank and laterally extending guide loops inclined at an angle to the plane of the shank, a thread take-up roll common to all the spool holders, said roll extending longitudinally of the machine substantially at right angles to the axes of the spool holders, means independent of the spool holder rotating means for rotating said roll, and means for moving said roll in the arc of a circle into a position over the spool holders.

JAN WILLEM LUBBERHUIZEN.
